PROPORTIONAL PUMPING APPARATUS

Vincent J. Gilmore, Wappingers Falls, N. Y., assignor to The De Laval Separator Company, New York, N. Y., a corporation of New Jersey

Application July 31, 1947, Serial No. 765,169

5 Claims. (Cl. 103—6)

1

This invention relates to pumping apparatus for delivering two liquids in predetermined relative proportions, as for the purpose of mixing the liquids for chemical reaction. More particularly, the invention relates to an improved proportional pumping apparatus of the type having a pair of reciprocating pumps for the respective liquids, which is rugged and durable in construction and is adapted to pump the liquids at high delivery rates in accurately measured proportions.

In proportional pumping apparatus as commonly used heretofore, the reciprocating pumps for the two liquids have their pistons interconnected so that they move in unison, at least over part of the respective pumping strokes. The intake and discharge valves for the pumps are operated by the pumps themselves; that is, they are actuated directly by the respective pistons or piston rods, or they are in the form of check valves operated by the liquids at each end of the respective piston strokes. It has been found that in such apparatus the proportioning of the two liquids is not accurate enough for some purposes, due largely to the fact that the opening and closing movements of the pump valves do not occur in sufficiently accurate and uniform timed relation to the piston strokes, because of sticking of the valves or malfunctioning of the valve operating connections. This inaccuracy of the proportioning is particularly pronounced in apparatus of large capacity for pumping highly viscous liquids, such as vegetable and animal oils.

The object of the present invention, therefore, is to provide an improved proportional pumping apparatus adapted to deliver the liquids in proportions which are maintained accurately within extremely close limits, even at high capacities and under severe conditions of use.

A pumping apparatus made in accordance with the invention comprises a pair of reciprocating pumps for the respective liquids to be proportioned, valve mechanism connected by a separate duct to each pump cylinder, and a power source for actuating the valve mechanism in synchronism with the pump pistons, whereby each liquid is first drawn through the valve mechanism and the connected duct to the corresponding pump cylinder during one stroke of the piston, and is then forced back through the duct and valve mechanism and through an outlet from the latter during the next stroke of the piston. Preferably, the valve mechanism is of the rotary type and includes a separate valve housing and rotor for each pump, the two rotors being con-

2

nected to each other and to the power source for the pistons; and in order to obtain continuous flow from the apparatus each housing is connected by a separate duct to an additional pump for the corresponding liquid, so that the two valves control the flow to and from a pair of parallel-operating pumps for each liquid. This construction affords a high degree of flexibility to the apparatus, in that an additional valve mechanism can be connected in parallel to the existing valve mechanism when the latter is insufficient to accommodate the full pumping capacity; or the pumping capacity can be increased by simply connecting additional pumps to the respective valve housings, without the necessity of any additional valve mechanism.

Since the valve mechanism is driven positively and continuously in synchronism with the pump pistons, the apparatus is adapted to maintain an accurate proportioning of the pumped liquids at all times. It is important, of course, that the duct connection for each pump be changed from the inlet to the outlet of the valve mechanism, or vice versa, at the end of each piston stroke and before the next stroke is commenced. Otherwise, the apparatus may be damaged or the accuracy of the proportioning may be impaired, or both. Accordingly, the apparatus is so constructed that the pistons have a short dwell after completion of each stroke, so that the valve mechanism will have ample time to reverse the pump connections through the ducts before the pistons begin their next strokes. For this purpose, I prefer to connect the power source to the pistons through a reciprocating crank arm, or the like, which includes an adjustable dash-pot operable to provide a lost motion when the crank arm reverses its motion at each end of its stroke.

In its preferred form, the apparatus also includes an adjustable connection between the power source and the valve rotors so as to permit a fine adjustment of the latter relative to the pump pistons, whereby the reversal of the valve connections for the pumps may be accurately timed in relation to the piston movements. This adjustable connection preferably comprises a chain and sprocket drive in which one of the sprocket wheels is rotatable relative to an adjacent disc secured to the wheel shaft. One of the disc and wheel members has a radial slot, while the other has a slot inclined at an acute angle to the first slot. A pin extends through the two slots to couple the members and is adjustable in the radial slot to cause relative rotation

of the members through an angular displacement corresponding approximately to the length of one of the chain links.

For a better understanding of the invention, reference may be had to the accompanying drawings, in which

Fig. 1 is a schematic view of a preferred form of the new apparatus;

Fig. 2 is a cross-sectional view of the valve and a pair of positive displacement pumps for one of the liquids, showing the valve inlet and outlet and the connections between the valve housing and the pumps;

Fig. 3 is an enlarged longitudinal sectional view of the "dash-pot" connection between the power source and the pump pistons;

Fig. 4 is an exploded perspective view of the means for adjusting the connection between the power source and the valve mechanism;

Fig. 5 is a front view of a modified form of the adjustable connection between the power source and the valve mechanism, and

Fig. 6 is a sectional view on the line 6—6 in Fig. 5.

For illustrative purposes, the apparatus will be described in connection with the pumping of vegetable or animal oil stock and the usual refining agent, it being understood that the oil and liquid reagent are to be pumped in predetermined relative proportions for a mixture of the two and subsequent refining of the oil. The apparatus may, of course, be used for pumping other liquids as well.

Referring to Fig. 1, the apparatus as illustrated comprises a power source, such as an electric motor 10 driving through a gear reduction and speed control device 11, so as to drive a sprocket wheel 12 and a crank 13. The sprocket wheel 12 is connected through an endless chain 14 to a sprocket wheel 15 on a shaft 16 which is rotatable in the frame (not shown) of the apparatus, the wheel 15 rotating synchronously with wheel 12 but at one-half the angular speed of the latter. At its opposite ends, the shaft 16 is connected to the rotors of valves 17 and 18 for the liquid reagent and the oil stock, respectively.

The crank 13 is connected through co-acting crank arm sections 20 and 21, forming a dash-pot which will be described presently, to the depending arm 22 of a walking beam 23 adapted to rock on a pivotal axis 24. The beam 23 carries at its opposite ends a pair of transverse rods 25 and 25^a. Pistons 26 and 27 are connected to the opposite end portions of rod 25 and form the movable parts of single-acting, positive displacement pumps 28 and 29 for the oil and the reagent, respectively. Similarly, the rod 25^a is connected at its opposite end portions to pistons 26^a and 27^a forming the movable parts of single-acting, positive displacement pumps 28^a and 29^a for the oil and the reagent, respectively.

The valves 17 and 18 have inlets 31 and 32 for the reagent and the oil stock, respectively, leading from suitable tanks or other sources (not shown) for the two separate liquids. The oil valve 18 is connected by separate ducts 33 and 33^a to the oil pumps 28 and 28^a, respectively; and the reagent valve 17 is connected by separate ducts 34 and 34^a to the reagent pumps 29 and 29^a, respectively. As will be described in greater detail presently, the rotors of valves 17 and 18 are driven together so as to connect the pumps 29—29^a and 28—28^a first to the inlets 31 and 32 and then to outlets 35 and 36, respectively, whereby the oil and reagent will flow first in one direc-

tion and then in the other direction in the ducts 33—33^a and 34—34^a. Preferably, the ducts 33 and 34 communicate with pressure relief valves 37 and 38 having drain pipes 39 and 40, respectively, and the ducts 33^a and 34^a communicate with pressure relief valves 37^a and 38^a having drain pipes 39^a and 40^a, respectively. The outlets 35 and 36 from the respective valves 17 and 18 lead through air traps 41 and 42 to a common pipe 43 where the two proportional liquids are mixed and passed on to a further stage 44 in the refining process.

The valves 17 and 18 are identical in construction, and therefore a description of the valve 18 will suffice. As shown in Fig. 2, the valve 18 comprises a frusto-conical housing 46 which is closed at its ends. The oil inlet 32 leads into the bottom of the housing, while the oil outlet 36 leads from the top of the housing in diametrically opposed relation to the inlet. Ports 47 and 47^a open into diametrically opposed sides of the valve housing, so that these ports and the inlet 32 and outlet 36 are spaced 90° apart around the conical periphery of the housing. Within the housing 46 is a frusto-conical valve member or rotor 48 having two diametrically opposed longitudinal vanes 49 and 50. The vanes 49 and 50, which are slightly wider than each of the four ports in the housing, fit closely against the peripheral wall and the end walls of the housing and divide the interior thereof into two diametrically opposed, arcuate chambers 51 and 52. The valve rotor 48 is adapted to be rotated about its axis so that the chambers 51 and 52 move continuously around the interior of the valve housing.

The ports 47 and 47^a are connected through the ducts 33 and 33^a to the cylinders 54 and 54^a of pumps 28 and 28^a, respectively. Each cylinder is provided at its open end with a cap 55 which retains a packing gland 56 around the piston of the pump.

As previously mentioned, the crank arm sections 20 and 21 form a dash-pot between the crank 13 and the walking beam 23 for actuating the pistons. More particularly, the section 20 has a longitudinal bore or chamber 58 which is open at one end, the bore having an annular recess or enlargement 59 intermediate its ends (Fig. 3). The adjacent section 21 has a plunger or slideable part 21^a extending into bore 58, and a sleeve 60 secured to plunger 21^a, as by means of a transverse pin 21^b. The sleeve 60 fits closely in bore 58 and has an annular external recess 61 which, with the recess 59, forms an annular oil chamber having a supply opening normally closed by a threaded plug 59^a. At each end of its recess 61, the sleeve 60 has longitudinal oil grooves 62 leading to the adjacent end of the sleeve. Near the outer end of sleeve 60 is a guide bushing 63 threaded in bore 58 and having a central opening in which plunger 21^a is slideable. The bushing 63 also has a recess for sealing rings 64 which are clamped in position around the plunger by a metal ring 65 held at one end by a cap 66 threaded on the bushing. At the outer end 67 of section 20 is a washer 68 which is engaged by a shoulder on the bushing when the latter is screwed into bore 58, whereby a clearance space 69 is provided between the inner end of the bushing and the opposing shoulder formed by the outer end of sleeve 60 when the plunger is in its innermost position in the bore.

With the parts positioned as shown in Fig. 3, the section 20 is moving to the left and engages

the inner end of plunger 21^a and sleeve 60 so that the latter parts move to the left with section 20. When section 20 reaches the end of its stroke and reverses its movement, the load (represented by the pump pistons) on plunger 21^a will prevent the latter from moving with section 20 until the inner end of bushing 63 engages the opposing end of sleeve 60. However, such engagement cannot occur until the oil is forced out of clearance space 69 and a corresponding volume of oil has been forced into the clearance space which, due to movement of the bore relative to the plunger and sleeve, forms at the closed end of the bore. The time delay thus provided in the plunger movement depends, of course, upon the extent of the clearance space 69 and upon the rate of flow through grooves 62 which, in turn, depends upon the size and number of the grooves. It will be understood that a similar time delay is provided at the next reversal of the movement of section 20, since the plunger will not be engaged by the closed end of the bore until the oil is forced out of the intervening clearance space and a corresponding volume of oil is simultaneously returned to the clearance space 69 which forms during the movement of the bore relative to the plunger and sleeve. By substituting a washer 68 of different thickness, the length of the clearance space 69 and therefore the time delay may be varied as desired.

The sprocket wheel 15 is adjustable angularly on its shaft 16. As shown in Fig. 4, a disc 70 is splined to shaft 16 and has a projecting hub 71 which fits into the central opening in wheel 15, the wheel being rotatable on the hub. The disc also has a radial slot 72, and the sprocket wheel has a slot 73 extending at an acute angle to slot 72, the slot 73 preferably extending at an angle of about 45° to a radius intersecting the latter. The length of slot 73 is such that its effective length, referred to a tangent to the radius taken at either end of the slot, will equal the length of one link of chain 14. A bolt 74 extends through the slots 72 and 73, and by adjusting the radial position of the bolt in slot 72, the angular position of the wheel 15 on its shaft may be varied. The sprocket wheel is clamped in its adjusted position on disc 70 by a nut 75 threaded on the projecting end of the bolt. If desired, the disc may be provided with arcuate slots 76 for receiving additional clamping bolts 77 which are threaded in openings 76^a in the sprocket wheel.

A modified form of the adjustable sprocket wheel is shown in Figs. 5 and 6. As there shown, the wheel 15^a is rotatable on the hub 71^a of a disc 70^a splined to shaft 16. A screw 78 extends radially in slot 72^a in the disc and has a block 79 threaded thereon. A bolt 74^a projects from the block into slot 73^a in wheel 15^a, the slot 73^a extending at an acute angle to an intersecting radius, as shown in Fig. 5. When screw 78 is turned, it moves block 79 radially inward or outward in slot 72^a, so that the cam action of the bolt in slot 73^a causes wheel 15^a to rotate relative to the disc and the shaft 16. The wheel and disc may be clamped together by bolts 77^a after adjustment of screw 78.

The operation of the apparatus is as follows: The pump pistons 26, 27 and 26^a, 27^a are reciprocated by crank 13, the crank arm sections 20, 21 and walking beam 23, while the rotors of valves 17 and 18 are driven together continuously by shaft 16 from sprocket wheels 12 and 15 and their interconnecting chain, in synchronism with the piston movements. However, the sprocket wheel

15 and the crank 13 are driven at different speeds, as pointed out previously, so that the crank and therefore the pump pistons will undergo two complete cycles during each complete revolution of shaft 16 and the valve rotors. Thus, assuming that rotor 48 of the oil valve rotates clockwise as shown in Fig. 2, the oil piston 26 will be moving downwardly and the other oil piston 26^a will be moving upwardly when rotor 48 is in the position illustrated. Consequently, oil is forced out of cylinder 54 through duct 33, arcuate chamber 51 and outlet 36, while oil flows in through inlet 32 and through arcuate chamber 52 and duct 33^a to the other oil cylinder 54^a. Each piston reaches the end of its stroke at or slightly before the instant when the vanes 49 and 50 reach the ports 47 and 47^a, respectively. From this instant, a short time interval elapses before the vanes 49 and 50 can pass over the respective ports to their opposite sides; but during this interval the time delay afforded by the dash-pot connection 20, 21 prevents the pistons from commencing their next strokes. When the pistons commence their next strokes, the vanes will have moved far enough to connect duct 33 through chamber 52 to inlet 32, and to connect duct 33^a through chamber 51 to outlet 36. Accordingly, the upward stroke of piston 26 will permit oil to flow into its cylinder from inlet 32, and the downward stroke of piston 26^a will force oil from its cylinder through outlet 36.

The pistons 26 and 26^a will reach the ends of their respective upward and downward strokes at or slightly before the instant when vanes 49 and 50 completely reach the ports leading to outlet 36 and inlet 32, respectively. Because of the time delay provided by dash-pot connection 20 and 21, the pistons will not commence their next strokes until after vanes 49 and 50 have passed over the respective outlet and inlet ports by moving clockwise beyond the latter. Thereupon, the downward stroke of piston 26 forces oil through duct 33 and chamber 52 to the outlet, and the upward stroke of piston 26^a allows oil to flow in from inlet 32, chamber 51 and duct 33^a, whereby a new cycle for each piston is commenced.

The operation of valve 17 is the same as that previously described in connection with valve 18. Piston 27 forces reagent through duct 34, valve 17 and outlet 35 at the same time that piston 26 forces oil through outlet 36 and while pistons 27 and 27^a allow oil and reagent to enter from inlets 32 and 31 through ducts 33^a and 34^a, respectively. The valves 17 and 18 reverse their respective connections at the same instant, and the pistons 27 and 27^a move in unison with the pistons 26 and 26^a, respectively. Accordingly, the reagent and the oil will flow substantially continuously through the respective outlets 35 and 36 for subsequent mixture in pipe 43. The relative proportions of the outflowing oil and reagent will depend, of course, upon the effective areas of the pistons 26, 26^a in relation to the effective areas of pistons 27, 27^a.

The relief valves 37, 37^a and 38, 38^a will open in response to excessive pressures which may be created accidentally in the respective ducts, so that the liquid will escape through the relief valve and its drain pipe and thereby prevent damage to the apparatus. The air traps 41 and 42 are adapted to remove air from the liquids and reduce the pressure pulsations incident to the pumping action.

By means of the adjustable mounting for

sprocket wheel 15, the position of the valve rotors may be readily and accurately adjusted relative to the pump pistons, to cause the valve connections to be reversed in the proper timed relation to the piston movements. In practice, the chain 14 is arranged on sprocket wheel 15 in a position as near as possible to that corresponding to the correct timing, and the final adjustment for less than the length of a chain link is made by adjusting the relative positions of disc 70 and wheel 15, as previously described.

It will be apparent from the foregoing that I have provided a proportional pumping apparatus in which the valve mechanism for reversing the pump connections is driven continuously and positively in synchronism with the pistons, so that the apparatus can be operated at high capacity to maintain within extremely close limits the proportioning of even highly viscous and sticky liquids. Also, with the new apparatus the pumping capacity can be easily increased by simply connecting additional pumps to the valve ducts 33, 34 or 33^a, 34^a, it being unnecessary to provide additional valve mechanism; and if the pumping capacity is too great to be handled by the existing valve mechanism, additional valve mechanism can readily be connected in parallel thereto. The added pumps can be driven from the rods 25, 25^a on the walking beam, or from extensions of these rods. The additional valve mechanism can be driven from shaft 16.

The apparatus is preferably arranged so that the liquids to be proportioned flow into the respective pumps by gravity, whereby the feed through inlets 31 and 32 is not dependent upon suction created by the pumps.

I claim:

1. A proportional pumping apparatus for delivering two liquids in predetermined relative proportions, which comprises a pair of cylinders for one of the liquids, a second pair of cylinders for the other liquid, a piston reciprocable in each cylinder, a rod connected to one piston of each of said pairs of cylinders, a second rod connected to the other pistons, a rocker arm pivoted intermediate its ends and connected at its end portions, respectively, to the rods, a valve housing for each of said pairs of cylinders and having a separate inlet and outlet, ducts connecting each valve housing with the respective cylinders, a valve rotor coacting with each housing and movable to connect one of the corresponding cylinders to the housing inlet and the other to the housing outlet through the respective ducts and then to reverse said last connections, a driving connection extending between the valve rotors,

and mechanism for operating said rocker arm and driving connection in synchronism.

2. A proportional pumping apparatus for delivering two liquids in predetermined relative proportions, which comprises a ported pump cylinder for each of the respective liquids, a piston reciprocable in each cylinder, valve housing means for each pump cylinder having an inlet and an outlet for one of the respective liquids, a duct leading from the port of each pump cylinder to the corresponding housing means, valve rotor mechanism coacting with each of the housing means and mounted for continuous movement to connect each duct alternately to the corresponding inlet and outlet, actuating means, and separate driving connections leading from the actuating means to each of the pump pistons and the valve rotor mechanism for actuating the same in timed relation.
3. Apparatus as defined in claim 2, comprising also a lost-motion device forming part of said separate driving connection to the pump pistons.
4. Apparatus as defined in claim 2, comprising also a releasable device forming part of said separate driving connection to the valve rotor mechanism, said last device being releasable to permit adjustment of the valve mechanism relative to the actuating means.
5. Apparatus as defined in claim 2, comprising also a releasable device forming part of said separate driving connection to the valve rotor mechanism, said last device being releasable to permit adjustment of the valve mechanism relative to the actuating means, and a lost-motion device forming part of said separate driving connection to the pump pistons.
